UNITED STATES PATENT OFFICE.

JAMES T. FULLER, OF DALLAS, TEXAS.

COMBINATION HEATING AND COOKING STOVE.

Application filed December 2, 1927. Serial No. 237,178.

This invention relates to new and useful improvements in combination heating and cooking stoves.

One object of the invention is to provide a readily portable stove which may be quickly and easily converted from a heating stove into a cooking stove and as easily returned to its normal condition.

Another feature of the invention is to provide a stove which may be used as a cooking stove in warm weather and also utilized as a heating stove in cold weather.

Another object of the invention is to provide a stove provided with movable parts for concealing, to a large extent, the cooking elements when it is not desired to use the same.

A construction designed to carry out the invention will be hereinafter described, together with other features of the invention.

The invention will be more readily understood from a reading of the following specification and by reference to the accompanying drawings, in which an example of the invention is shown and wherein:

Fig. 1 is a front elevation of a stove constructed in accordance with my invention, the upper portion of the stove being broken away and parts illustrated in section,

Fig. 2 is a rear elevation of the same,

Fig. 3 is a plan view, the top cover being slid to the cooking position,

Fig. 4 is an enlarged vertical sectional view taken on the line 4-4 of Fig. 1, and

Fig. 5 is a plan view of the top cover member.

In the drawings the numeral 10 designates a rectangular vertical stove body supported on legs and having a transverse opening 11 in the lower portion of its front wall. The opening 11 forms the front of a heating chamber 12 within the stove. The top of this chamber is defined by a transverse partition 13 just above said opening and forming the bottom of an oven 14. In the rear portion of the heating chamber a transverse gas burner 15 is mounted.

A panel 16 hinged within the chamber 12 contiguous to the bottom of the opening 11 is normally inclined within the chamber and has its upper end resting upon a transverse bracket 17. This panel forms a deflector for diverting the heat currents outward through the opening 11. This panel is provided with a friction lug 18 near its upper

end adapted to engage the upper edge of the opening 11 when the panel is swung forward to close the opening 11, as is shown in dotted lines in Fig. 4.

It will be seen that when the panel is open the heat units will be deflected through the opening 11 and the stove utilized as a heater, but when the opening is closed by the panel the heat units will be confined in the chamber 12 and the oven 14 thus more effectively heated.

The oven is provided with a door 19 hinged on the back of the stove, as is shown in Figs. 2 and 3. The oven has a false front wall 20 spaced inwardly from the front wall 70 of the stove so as to provide a vertical space 21 therebetween. The top wall 22 of the oven forms the bottom of a transverse burner chamber 23 having a top 24 provided with eyes 25. Gas burners 26 are mounted in 75 the chamber 23 under the eyes 25. These gas burners are connected with a manifold 27 by means of supply pipes 28 including cocks 29.

For supplying the stove with gas a T 30 is 80 provided with a nipple 31 for connecting with a hose or other medium for conducting gas to said T. The T is connected in a feed pipe 32 connected at its upper end with the manifold 27 and at its lower end with the 85 burner 15. A cutoff valve 33 is connected in the pipe 32 below the T 30 so that the supply of gas to the burner 15 may be controlled or cut off. This makes a simple arrangement of gas supply pipes, but it is obvious 90 that other arrangements and locations could be made.

For concealing the eyes 25 and the manifold 27, I provide a cover member composed of two sections 34 and 35 hinged together. 95 The vertical space 21 is of such depth as to receive the plate-like section 34, whereby the narrow section 35 is left standing upright above the top 24, as is shown in Fig. 4. This upstanding section forms a guard when the eyes 25 are uncovered. When it is desired to use the stove merely as a heater, the cover member is pulled upwardly so as to extend over the top 24 with the section 35 hanging down over the manifold 27, as is shown in 100 105 dotted lines in Fig. 4.

Various changes in the size and shape of the different parts, as well as modifications and alterations, may be made within the scope of the appended claims.

What I claim, is:

1. In a combination heating and cooking stove, a stove body having a heating chamber in its lower portion provided with an open front, means for closing said opening arranged to be positioned as a heat deflector opposite said open front when not closing said opening, an oven in the upper part of the stove body, a burner in the heating chamber, a cooking burner in the top of the stove, and a movable cover for concealing the cooking burner.

2. In a combination heating and cooking stove, a stove body having a heating chamber at its lower portion other than an oven, a burner chamber at the top of the body having an eye in its top, a gas burner in the burner chamber, the body having a storage space, and a cover member comprising hinged sections removably stored in said space when removed to expose the eye of said burner chamber, one of which sections rests upon the top of the burner chamber when withdrawn and the section is folded at an angle thereto to form a front guard.

3. In a combination heating and cooking stove, a stove body, a heating chamber in the lower portion of the body having an opening in its front, a bracket within the heating chamber, a closure panel hinged in the heating chamber at the base of the front opening and supported at an angle by said bracket, said closure panel closing said chamber opening when swung, an oven immediately over the heating chamber, a gas burner at the upper portion of said heating chamber contiguous to the bottom of the oven, a burn-

er chamber in the stove body immediately above the oven and having a gas burner therein and provided with an eye at its top, and a movable flat cover plate for the top of said burner chamber.

4. In a combination heating and cooking stove, a stove body having a heating chamber in its lower portion provided with an open front, means for closing said open front arranged to be positioned as a heat deflector opposite the open front when not closing the same, an oven in the upper part of the stove body, and a cooking burner in the top of the stove.

5. In a combination heating and cooking stove, a stove body having a heating chamber in its lower portion provided with an open front, a closure plate pivoted at its lower edge at said open front and adapted to swing into said chamber to act as a deflector opposite said front, a burner in the heating chamber, and a cooking burner in the top of the stove.

6. In a combination heating and cooking stove, a stove body having a heating chamber in its lower portion other than an oven, an oven above said chamber having a vertical storage space at its rear, a burner chamber above said oven having an eye in its top, a burner aligned with said eye, and a rigid imperforate cover plate adapted to lie horizontally upon the top of the burner chamber and to be removably stored in said space when moved to expose the eye of said burner chamber.

In testimony whereof I affix my signature.
JAMES T. FULLER.
